UNITED STATES PATENT OFFICE.

OTTO FELIX ROGGENKAMP, OF SENECA, KANSAS.

HEATER.

SPECIFICATION forming part of Letters Patent No. 728,618, dated May 19, 1903.

Application filed November 4, 1902. Serial No. 130,069. (No model.)

To all whom it may concern:

Be it known that I, OTTO FELIX ROGGENKAMP, a citizen of the United States, and a resident of Seneca, in the county of Nemaha 5 and State of Kansas, have invented new and useful Improvements in Heaters, of which the following is a full, clear, and exact description.

This invention relates to improvements in heaters, the object being to provide a self-feeding heater of simple construction in which corncobs or long sticks of wood may be used as a fuel.

I will describe a heater embodying my invention and then point out the novel features in the appended claim.

Reference is to be had to the accompanying drawings, forming a part of this specification, in which similar characters of reference indicate corresponding parts in both figures.

Figure 1 is a perspective view of a heater embodying my invention; and Fig. 2 is a sectional elevation thereof, a portion of the casting being broken away to show the plugging valves employed.

Referring to the drawings, 1 designates the base or fire-box of the heater, having a door-opening 2 at one end for the removal of ashes or the like. Mounted on the base and communicating therewith is a feeding-drum 3 and a heating-drum 4. The feeding-drum 3 has a cover 5, and communicating with the heating-drum 4 is a smoke-pipe 6. At the opposite sides of the door at the front of the base or heating-box are upwardly-extended draft-tubes 7 8. The upper ends of these tubes are made fun-

nel shape to receive plug-valves 9 10, by means of which the draft may be regulated. These two valves 9 10 are connected to rods 11 11^a, which slide in guides 12 12^a, attached to the 40 feeding-drum 3, and the valves may be held as adjusted by means of thumb-springs 13 13^a, attached to the drum, and also attached to the rods 11 11^a are finger-pieces 15.

In operation the drum 3 is to be filled with 45 fuel—such, for instance, as corncobs or long sticks of wood standing upright. The combustion will take place in the base or fire-box 1, and the products of combustion will pass up through the drum 4 and the pipe 6. It is 50 obvious that a heater embodying my invention may be made of comparatively light metal, and therefore will be very cheap to manufacture.

Having thus described my invention, I 55 claim as new and desire to secure by Letters Patent—

A heater comprising a base or fire-box, a feeder-drum communicating therewith, a heating-drum communicating with the base, 60 a draft-tube extended upward from the front end of the base, a plug-valve for said tube, a rod extended upward from the valve, guides on the feeder-drum for said rod, and a spring on said drum engaging with said rod. 65

In testimony whereof I have signed my name to this specification in the presence of two subscribing witnesses.

OTTO FELIX ROGGENKAMP.
